UNITED STATES PATENT OFFICE

ROSANNA DU FORA ULMAN, OF AURORA, ILLINOIS, ASSIGNOR TO INTERNATIONAL CORSET COMPANY, OF AURORA, ILLINOIS, A CORPORATION OF ILLINOIS

CORSET

Application filed November 22, 1926. Serial No. 149,843.

This invention relates to corsets, and as herein shown, is embodied in a combination of brassière and corset, commonly designated as a one-piece garment.

One of the objects of the invention is to construct a garment particularly adapted to persons inclined to stoutness, which will exert a flattening effect upon certain portions of the figure, namely: over the abdomen and on the sides of the hips toward the back, appreciably below the normal waist line.

Another object is to produce a garment which will restrain, and give a flattened appearance to, the parts of the body above mentioned, without resorting to the familiar boning or other stiffening means.

It is well understood that certain portions of a corset are subject to considerable strain, particularly when the wearer is in a sitting posture, and are liable to stretch out of shape and to fail to exert a desired confining effect. One of the objects of my invention is to produce a garment which will obviate this objection; produce the desired flat effect and at the same time resist strains at the points where stretching would ordinarily occur.

The invention consists in the arrangement and combination of parts illustrated in the drawings, described in the specification and more particularly pointed out in the claims.

In the drawings:

Figure 1 is a plan view of the outside of a one piece garment constructed in accordance with and embodying my invention.

Figure 2 is a sectional view, enlarged, through one panel of the garment; the section being taken in the plane of the dotted line 2-2 of Figure 1.

Figure 3 is a plan view of the outside of a portion of the garment, showing a modified form of the invention.

Figure 4 is a similar view showing another modified form.

Figure 5 is a sectional view through one panel, enlarged, of the modification shown in Figure 4, the section being taken in the plane of the line 5-5 on Figure 4.

Figure 6 is a detail view of a portion of the garment shown in Figure 1.

Referring now to the construction shown

in Figures 1 and 2, the garment as a whole is indicated by the letter A, and is composed of a back member B, two similarly constructed side members C, C, and a front member D. The back member B may be of any suitable construction, but as herein shown is composed of a panel, the major portion of which is constructed substantially as shown in United States Letters Patent to Charles H. Schopbach, Reissue No. 13,698, dated March 10, 1914, and therefore need not be further herein described.

The side members C, C, are constructed of a plurality of panels, as shown in Figure 1, indicated at 1, 2 and 3, extending longitudinally of the garment. A description of one of the side members C will suffice for both.

The front member D may be of any familiar construction, and as herein shown, it consists of a single panel 4, having a plurality of hooks 5 adapted to be engaged by the eyes 6 on the panel 1 of the side member.

The usual shoulder strap members E, E, are secured to the upper portion of the garment, and a plurality of hose supporters F are secured to the lower margin of the garment in the usual manner. One set of hose supporters, as will be noticed, is attached to and depend from the inner band member G. Such member is preferably used, but its individual construction has no direct connection with the present invention and need not be further described.

As shown in Figure 1, the panel 1 of the side member C is provided, in a position substantially over the side of the abdomen, toward the front, with a reinforcement strip 7 of material similar to that of which the panel is made, indicated as a whole at 7. The strip is secured to the panel 1 by lines of stitches 8 and 9. The line of stitches 10 by which the panel 1 is secured to the panel 2 of course crosses the strip 7 and secures its rear margin to the garment. The front margin of the strip 7 is secured by a line of stitches 10.

The strip 7 is made from a substantially rectangular blank and is provided with a plurality of tucks 11, extending transversely,

and deeper at one end (to-wit: the front end) than at the other; said tucks being maintained by lines of stitches 12, 12.

A similar strengthening strip 13 is secured by lines of stitches 14, 15, to the panel 3 of the side member C, but it will be observed that in this instance the tucks 16, maintained by stitches 17, 17, are deepest where the strip is secured to the back panel B. The strip 13 is secured along its front margin by the same stitches 18 which secure the adjacent margins of the panels 2 and 3, and is secured at its rear margin by stitches 19 by which the panel 3 is sewed to the back member B.

15 The panel 2, as shown, is composed of its upper portion 20 of ordinary fabric and the lower elastic portion 21.

It will be noted that the strengthening strip 13 is positioned lower in the garment than the strip 7 and is substantially below the normal waistline. The strip 7 reinforces the material of the panels 1 over that portion where the tendency to outward pressure by the abdomen occurs. The strip 13 reinforces the fabric of the panels 3 over that portion of the hips toward the back, where unusual outward pressure is exerted, especially when the wearer is in a sitting posture.

30 These strips 7 and 13 are peculiarly effective as reinforcing strips because of the tucked arrangement shown. In forming the tucks, the initial direction of the threads of the fabric forming the strips is changed, and lines of resistance are formed in a plurality of directions, which give to the panels equipped with said strips, a very great resisting power.

35 The result is quite different from and far superior to that attained by superimposing an ordinary reinforcing strip over the garment panel. This is diagrammatically indicated in Figure 6, where the parallel lines 22 indicate the direction of the longitudinal or warp threads of the fabric of which the panel 1 is made; and where the lines 23 indicate the direction of the longitudinal threads of the fabric of the strip 7 after the tucks 11 have been formed therein. It will be noted that the lines of threads 23 are substantially curved lines and cross the direction of the lines 22.

40 This arrangement of the tucks, in angular relation to each other, and in angular relation to the initial direction of the threads of the strips 7 and 13, when superimposed upon the respective panels of the garment, produces a novel and highly beneficial result.

45 In the modification shown in Figure 3, the panel 2 is entirely omitted and the panels 1 and 3 are widened and joined together along the longitudinal line 24. The strengthening strips 7 and 13 are of course made larger to correspond with the increased width of the panels 1 and 3.

50 In some instances it is desirable to get the strengthening effect of the tucks 11 and 16 without using the separate strips 7 and 13.

Such a modification is shown in Figure 4. The panels 1 and 3 are formed of a single piece of fabric 25, and provided with a plurality of tucks 26, held in position by stitching 27—the panels 25 being properly shaped by the reverse upper tuck 28.

55 I claim as my invention:

1. A corset comprising a plurality of connected longitudinally disposed panels of fabric, certain of said panels being provided with means whereby those portions of the garment which overlie the abdomen and the sides of the hips towards the back of the wearer, will resist outward pressure by said body parts, said means consisting of strips of fabric, the longitudinal threads of each strip being disposed at a plurality of angles to the direction of the longitudinal threads of the fabric panels of the garment to which said strips are attached.

60 2. A corset comprising a plurality of connected longitudinally disposed panels of fabric, certain of said panels being provided with means whereby the garment will resist outward pressure by portions of the body of the wearer, said means consisting of fabric strips provided with tucks angularly disposed with respect to each other, and superimposed upon the garment panels overlying the abdomen and upon the garment panels overlying the sides of the hips toward the back of the wearer, and the longitudinal threads of each strip being disposed at a plurality of angles to the direction of the longitudinal threads of the fabric panels of the garment.

65 3. A corset provided with superimposed permanently attached pressure-resisting sections, the fabric of which is folded and stitched to contract one longitudinal margin of each section, two of said sections being associated with the front of the corset below the waist line so that the contracted margins will be toward the center front of the garment, and two of said sections being associated with the back of the corset below the waist line so that the contracted margins will be toward the center back of the garment.

70 In testimony that I claim the foregoing as my invention I affix my signature, this 18th day of November, 1926.

ROSANNA DU FORA ULMAN.
